CLAIM

I claim the ornamental design for a river crossing stone sensory-integration training toy, as shown and described.

DESCRIPTION

FIG. 1 is a front view of a river crossing stone sensory-integration training toy;

FIG. 2 is a rear view of the river crossing stone sensory-integration training toy of FIG. 1;

FIG. 3 is a side view of the river crossing stone sensory-integration training toy of FIG. 1, the view from the opposite side being identical;

FIG. 4 is a top view of the river crossing stone sensory-integration training toy of FIG. 1;

FIG. 5 is a bottom view of the river crossing stone sensory-integration training toy of FIG. 1;

FIG. 6 is a perspective view of the river crossing stone sensory-integration training toy of FIG. 1, looking downward; and,

FIG. 7 is a perspective view of the river crossing stone sensory-integration training toy of FIG. 1, looking upward.

1 Claim, 7 Drawing Sheets
